(57) **CLAIM**

The ornamental design for a door facing, as shown and described.

DESCRIPTION

FIG. 1 is a front perspective view of my design; FIG. 2 is a front elevational view of FIG. 1; FIG. 3 is a rear elevational view of FIG. 1; FIG. 4 is an enlarged view of a portion of FIG. 2; FIG. 5 is a top plan view of FIG. 1; FIG. 6 is a bottom plan view of FIG. 1; FIG. 7 is a cross-sectional view taken along line 7-7 of FIG. 2; FIG. 8 is an enlarged view of a portion of FIG. 7; FIG. 9 is a left side elevational view of FIG. 1; FIG. 10 is a right side elevational view of FIG. 1; FIG. 11 is a cross-sectional view taken along the line 11-11 of FIG. 2; FIG. 12 is an enlarged view of a portion of FIG. 11; FIG. 13 is a front perspective view of a second embodiment of my design; FIG. 14 is a front elevational view of FIG. 13; FIG. 15 is a rear elevational view of FIG. 13; FIG. 16 is an enlarged view of a portion of FIG. 14; FIG. 17 is a top plan view of FIG. 13; FIG. 18 is a bottom plan of FIG. 13; FIG. 19 is a cross-sectional view taken along line 19-19 of FIG. 14; FIG. 20 is an enlarged view of a portion of FIG. 19; FIG. 21 is a left side elevational view of FIG. 14;

(Continued)

FIG. 22 is a right side elevational view of FIG. 14; FIG. 23 is a cross-sectional view taken along the line 23-23 of FIG. 14; and,

FIG. 24 is an enlarged view of a portion of FIG. 23.

The broken lines seen in FIGS. 1-4 and 13-16 are for purposes of illustrating portions of the door facing that form no part of the claimed design. The broken lines of alternating lengths throughout the figure views are for purposes of illustrating the locations and boundaries of enlarged views of portions of the door facing, and also form no part of the claimed design.

1 Claim, 14 Drawing Sheets
